ABSTRACT OF THE DISCLOSURE

This invention relates to linear crystal controlled oscillator circuits. The oscillator includes a frequency determining portion which is composed of two networks. The first network includes the frequency controlling crystal, whose admittance is highly dependent upon frequency. The second network, whose admittance is a linear function of frequency and a non-linear function of modulating voltage, includes a voltage controlled capacitance, to which the modulating voltage is applied. Parameters of the two networks are selected to make the frequency response of the oscillator linearly dependent on modulating voltage. The full specification should be consulted for a complete understanding of the invention.

Disclosure

My invention relates to electronic oscillators, and particularly to novel variable frequency, voltage controlled crystal oscillators.

Crystal oscillators are commonly employed where high frequency stability is desired. To obtain the advantages of crystal control without being restricted by the precise resonant frequency of particular crystals, various means have been devised for adjusting or modulating the frequency of such crystal oscillators. A common expedient is to use a semi-conductor, having a capacitance controlled by an applied voltage, connected in a frequency determining network with the crystal to form an oscillator control network. Such a network can be precisely tuned over a range of frequencies to a frequency dependent on the modulation voltage applied to the variable capacitance semi-conductor for use as a source of frequency modulated signals.

For that use, it is highly desirable that the frequency of the oscillator be linearly dependent on the applied modulating voltage. However, the semi-conductor devices which are voltage-variable capacitors, are highly non-linear in their response to applied voltage. While it is possible to construct a device exhibiting a linear relationship between applied voltage and capacitance, such devices are inherently quite expensive. Further, such devices are generally of low Q, high temperature sensitivity, and relatively large physical size.

In order to avoid this expense while obtaining a net linear relationship, it has been proposed to supply a non-linear voltage-variable capacitance device with a non-linear modulating voltage, thereby compensating for the non-linearity of the variable capacitance. Such a non-linear modulating voltage may be obtained with a series of properly interconnected diodes. However, such an arrangement is inherently expensive and is sensitive to changes in bias voltages. A further disadvantage of a device making use of a number of diodes is that the contact voltages of the individual diodes are sufficiently unpredictable that each network must be made up of carefully selected components.

It is, therefore, a primary object of my invention to provide a crystal oscillator, whose frequency, at least over a

range of interest, is linearly dependent on an applied modulating voltage.

It is possible to tune crystal oscillators in the vicinity of the parallel resonance frequency of the crystal. Parallel tuning avoids problems resulting from undesired shunt capacitances to ground. However, it is inherently possible to modulate the tuned frequency of a crystal controlled circuit over a broader range about the series resonance frequency than about the parallel resonance frequency. Basically, the reason for the above is that inharmonic resonance modes generally occur closer to the parallel resonance frequency than to the series resonance frequency, and frequency modulation cannot be carried into the region of inharmonic resonance without distortion. It is a particular object of my invention to make it possible to modulate a variable-frequency crystal-controlled oscillator about the series resonance frequency of the crystal in a manner linearly dependent on an applied voltage, and without interference by shunt capacitances.

Briefly, the above and other objects of my invention are attained by a crystal oscillator comprising a novel frequency determining circuit resonant at a frequency f that is linearly dependent upon an applied modulating voltage V_m over a range of frequencies, about a center frequency f_0 , to which the crystal can be "pulled" by circuit tuning. The frequency determining circuit consists of two parts. A first part comprises a network, including the frequency controlling crystal, whose admittance is highly dependent upon frequency. The second part comprises a network including the voltage-controlled capacitance and other passive components selected such that the equivalent admittance of the second network is, to a good approximation over the frequency range of interest, a function that is linear with frequency. The admittance of the network forming the second part of the circuit is also a non-linear function of modulating voltage. Thus, the admittance of the first portion of the frequency determining network, Y_x may be expressed as $Y_x = G_1(f)$. The admittance Y_m of the second portion of the circuit may be expressed as: $Y_m = G_2(V_m, f)$. The components are selected, in a manner to be described below, such that the frequency determining network is at parallel resonance, over the frequency range of interest, at a frequency determined by the modulating voltage V_m . Accordingly, $Y_m = -Y_x$. As it is desired that, over the range of interest, the frequency of operation be proportional to modulating voltage V_m , it is necessary that $f - f_0 = kV_m$, where k is a constant. A sufficient condition is that $G_1(f) = -G_2(V_m, f)$. While it is not in general possible to make the function G_1 have exactly the same form as G_2 over any appreciable range, I have discovered that it is quite practical to make G_1 substantially identical to G_2 over a practical range of frequencies by selection of the constants in two portions of the circuit in a manner to be described in detail below.

In general, while the variation of Y_m with V_m may be highly non-linear, for the practical range of interest noted the functions G_1 and G_2 will be representable by convergent series. Assume that both functions are represented in convergent series, with G_1 in ascending powers of $(f - f_0)$ and G_2 in ascending powers of V_m/V_b , where V_b is a constant reference voltage as follows:

$$G_1(f) = f[a_1(f-f_0) + a_2(f-f_0)^2 + a_3(f-f_0)^3 + \dots + a_n(f-f_0)^n + \dots]$$

$$G_2(V_m, f) = f \left[b_1 \left(\frac{V_m}{V_b} \right) + b_2 \left(\frac{V_m}{V_b} \right)^2 + b_3 \left(\frac{V_m}{V_b} \right)^3 + \dots + b_n \left(\frac{V_m}{V_b} \right)^n + \dots \right]$$

If $G_1(f)$ is to equal $-G_2(V_m, f)$, then

$$a_1(f-f_0) = b_1 \left(\frac{V_m}{V_b} \right)$$

$$a_2(f-f_0)^2 = b_2 \left(\frac{V_m}{V_b} \right)^2$$

$$a_3(f-f_0)^3 = b_3 \left(\frac{V_m}{V_b} \right)^3$$

•

•

•

$$a_n(f-f_0)^n = b_n \left(\frac{V_m}{V_b} \right)^n$$

•

•

As a practical matter, for design purposes the approximation to linearity will be sufficiently good if the first few terms of this series are equated. As will be pointed out below, in practice voltage controlled crystal oscillators made in accordance with my invention have better linearity than that indicated by the mathematical approximation.

The apparatus of my invention will best be understood in the light of the following detailed description, together with the accompanying drawings, of illustrative embodiments thereof.

In the drawings,

FIG. 1 is a block diagram of a voltage-controlled oscillator;

FIG. 2 is a block diagram of a voltage controlled frequency determining network useful in the oscillator circuit of FIG. 1;

FIG. 3 is a schematic wiring diagram of a crystal circuit forming a part of the network of FIG. 2;

FIG. 4 is a schematic diagram of the actual equivalent circuit of the apparatus of FIG. 3;

FIG. 5 is a schematic diagram of a useful approximate equivalent circuit for the apparatus of FIG. 3;

FIG. 6 is a schematic diagram of a modulating circuit forming a part of the apparatus of FIG. 2;

FIG. 7 is a graph of admittance versus frequency illustrating a non-linear mode of operation of the apparatus of FIG. 2;

FIG. 8 is a second graph of admittance versus frequency illustrating the operation of the apparatus of FIGS. 1 and 2 when constructed in accordance with my invention;

FIG. 9 is a schematic embodiment of an oscillator in accordance with a practical embodiment of my invention;

FIG. 10 is a graph of the impedance versus frequency characteristic of a crystal;

FIG. 11 is a diagram partially schematic and partially in block form illustrating a modification of the apparatus of my invention;

FIG. 12 is a schematic diagram of a crystal circuit suitable for use in the apparatus of FIG. 11;

FIG. 13 is a schematic diagram of the equivalent circuit of the apparatus of FIG. 12;

FIG. 14 is a schematic diagram of the theoretical circuit of FIG. 11 incorporating the circuits of FIGS. 9 and 13;

FIG. 15 is a schematic diagram of an actual circuit equivalent to the theoretical circuit of FIG. 14; and

FIG. 16 is a schematic diagram of a voltage controlled oscillator in accordance with a preferred embodiment of my invention.

In FIG. 1, I have shown a conventional voltage controlled crystal oscillator comprising an amplifier 1 connected to a frequency determining network 2. The circuit produces an output voltage V_0 having a frequency that is a function of an applied modulating voltage V_m .

While there are many ways in which a frequency determining network may be interconnected with an amplifier to act as an oscillator, typically the frequency determining network is a circuit that is resonant at the frequency of oscillation and selectively provides regenerative feedback to the amplifier at that frequency. Such a resonant circuit is illustrated schematically in FIG. 2, and comprises a crystal circuit generally indicated at 3 and a modulating circuit generally indicated at 4. The crystal circuit 3 has an admittance Y_x that is a function of frequency and the modulating circuit 4 has an admittance Y_m that is a function of frequency and also is a non-linear function of the applied modulating voltage V_m . As shown, the modulating circuit and the crystal circuit are connected in parallel, such that the equivalent admittance of the resonant circuit is $Y_x + Y_m$.

FIG. 3 shows a typical crystal circuit 3, for use in the parallel resonance mode. The circuit includes a frequency control crystal X connected in series with an inductor L_1' . A capacitor C_1 is connected in parallel with the crystal X, and a capacitor C_2 is connected in parallel with the inductor L_1' .

FIG. 4 shows the equivalent circuit, in which the schematic symbol for the crystal X has been replaced by the conventional equivalent network for a crystal which includes an inductance L_2' , a capacitor C_3 in series with the inductor L_1' , and a capacitor C_4 in parallel with the series combination of the inductor L_2' and the capacitor C_3 . In this equivalent circuit, as in others to be described, resistances have been ignored as irrelevant to the selection of the reactive components.

Since voltage controlled crystal oscillators are inherently limited to a frequency range close to the resonant frequency of the selected crystal, for practical purposes the circuit of FIG. 4 can be replaced by the simpler equivalent circuit of FIG. 5. In FIG. 5, the various capacitors of FIG. 4 have been replaced by a capacitor C_0 , and a capacitor having a capacitance $r C_0$, where r is a constant. L_1 in FIG. 5 is slightly greater than L_1' . The function of C_2 is to tune L_1 . It is small and can be ignored. If C_2 is ignored, it can be shown that the circuits of FIGS. 4 and 5 are canonical forms where

$$C_0 = C_1 + C_3 + C_4$$

$$r = \frac{C_1 + C_4}{C_3}$$

$$L_2 = \frac{L_2' C_3^2}{(C_1 + C_3 + C_4)^2} \approx \frac{L_2'}{r^2}$$

In terms of the equivalent circuit of FIG. 5, the admittance Y_x of the crystal circuit of FIG. 3 is given by:

$$(1) \quad Y_x = \frac{-j\omega C_0 (1 - \omega^2 L_2 r C_0)}{\omega^2 L_2 C_0 - (1 - \omega^2 L_2 r C_0) (1 - \omega^2 L_1 C_0)}$$

where $\omega = 2\pi f$ and f = frequency in cycles per second. By definition,

$$\omega_0^2 \triangleq \frac{1}{L_2 C_0}$$

and

$$\omega_s^2 \triangleq \frac{1}{L_1 C_0}$$

Then Equation 1 becomes

$$(2) \quad Y_x = \frac{-j\omega C_0 \left(1 - \frac{\omega^2}{\omega_0^2} \right)}{\frac{\omega_2}{r \omega_0^2} - \left(1 - \frac{\omega^2}{\omega_0^2} \right) \left(1 - \frac{\omega^2}{\omega_s^2} \right)}$$

Let $\omega_0 \triangleq 2\pi f_0$ and

$$\omega_s \triangleq 2\pi(f_0 + \Delta f_0)$$

where f_0 is the parallel resonant frequency of the crystal, Δf_s is the frequency difference between f_0 and the series resonant frequency of the series combination $L_1 C_0$, and ω_s is the series resonant angular frequency of this combination in radians per second. The term ω may be written as $\omega = 2\pi (f_0 + \Delta f)$, where $\Delta f = f - f_0$. With these definitions, and ignoring terms such as

$$\left(\frac{\Delta f^2}{f_0^2} \right)$$

and

$$\left(\frac{\Delta f_s^2}{f_0^2} \right)$$

that are inherently very small with respect to other terms over the operating frequency ranges of interest, it can be shown that

$$(3) \quad Y_x = \frac{-j\omega C_0 \left(\frac{-2\Delta f}{f_0} \right)}{\frac{1}{r} \left(1 + \frac{2\Delta f}{f_0} \right) + \left(\frac{2\Delta f}{f_0} \right) \left(\frac{2\Delta f_s}{f_0} - \frac{2\Delta f}{f_0} \right) \frac{1 + \frac{2\Delta f_s}{f_0}}{1 + \frac{2\Delta f}{f_0}}}$$

Define

$$y \triangleq \frac{\Delta 2\Delta f}{f_0}$$

and

$$D \triangleq \frac{2\Delta f_s}{f_0}$$

Equation 3 can then be written as:

$$(4) \quad Y_x = \frac{j\omega C_0 y}{\frac{1}{r} (1+y) + y \left(\frac{D-y}{1+D} \right)}$$

Rewriting,

$$Y_x = \frac{j\omega C_0 y}{1+y+ry \left(\frac{D-y}{1+D} \right)}$$

The term $ry \left(\frac{D-y}{1+D} \right)$ can be written as:

$$ry \frac{(D-y)(1-D)}{(1+D)(1-D)} = ry \frac{(D-y-D^2+yD)}{(1-D^2)}$$

since $D < 1$, $(1-D^2) \approx 1$ and (5) can be approximated as:

$$Y_x = \frac{j\omega C_0 y}{1+y+ry(D-y-D^2+yD)}$$

or

$$(6) \quad Y_x = \frac{j\omega C_0 y}{1+y(1+rD-rD^2)-ry^2(1-D)}$$

With the use of the binomial expansion of $(1+x)^{-1}$, where $x = y(1+rD-rD^2) - ry^2(1-D)$, and approximations based on the facts that $r > 1$, $rD < r$, and $2rD^2 < r$, it can be shown that, to a sufficient approximation, Y_x is given by:

$$(7) \quad Y_x = j\omega C_0 y [1 - ryD + y^2r(1+rD^2) + \dots]$$

Equation 7 can evidently be expressed as

$$Y_x = f[G_3(f)] = G_1(f)$$

Next, the derivation of the admittance Y_m of the modulating circuit, as $Y_m = G_2(V_m f) = f[G_4(V_m)]$, will be considered. Finally, the construction of the circuits necessary to make $G_3(f) = -G_4(V_m)$ over a practical range of frequencies and modulating voltage will be described.

FIG. 6 shows a modulation circuit usable in the configurations of FIGS. 1 and 2. As shown, the circuit generally indicated at 4 includes a variable capacitance diode D arranged to be supplied with a suitable bias voltage V_b to set the operating point, and a modulating voltage

V_m , which may be either a varying or an adjustable constant direct voltage, positive with respect to ground, and supplied to the diode through a relatively large resistor R_1 . DC isolation is provided by a pair of capacitors C_8 and C_9 connected in series with the diode D. The capacitances of C_8 and C_9 are usually very large in comparison with the capacitance of the diode D and therefore have relatively little effect on the value of the capacitance of the branch of the circuit in which the diode D appears. In general, the capacitor C_8 will be a component specifically provided for the purpose, but the capacitor C_9 may be omitted if the power supply terminal from which the bias voltage V_b is supplied is at AC ground potential. As shown, the path including the capacitors C_8 and C_9 and the diode D is connected across the input terminals a and b of the modulating circuit 4. A capacitor C_{10} and an inductance L_3 are connected in parallel with these components. If the sum of the capacitances C_8 and C_9 and the capacitance of the diode D is represented as C_d , it will be apparent from elementary considerations that the admittance Y_m of the modulating circuit, as seen either from the input terminals a and b or from the output terminals c and d , will be given by

$$25 \quad Y_m = \frac{-j}{\omega L_3} + j\omega C_{10} + j\omega C_d$$

The capacitance C_d may be represented as

$$30 \quad C_d = \frac{C_b}{\sqrt{1 - \frac{V_m}{V_b}}}$$

Accordingly, the admittance Y_m of the modulating circuit can be expressed as a function of the passive components and of the voltages V_m and V_b as

$$35 \quad (8) \quad Y_m = j \left(\frac{-1}{\omega L_3} + \omega C_{10} + \frac{\omega C_b}{\sqrt{1 - \frac{V_m}{V_b}}} \right)$$

$$40 \quad \text{Let } F \left(\frac{V_m}{V_b} \right) \triangleq \left(1 - \frac{V_m}{V_b} \right)^{-\frac{1}{2}}$$

Expanding F in MacLaurin's series,

(9)

$$45 \quad F \left(\frac{V_m}{V_b} \right) \approx 1 + \frac{1}{2} \left(\frac{V_m}{V_b} \right) + \frac{3}{8} \left(\frac{V_m}{V_b} \right)^2 + \frac{5}{16} \left(\frac{V_m}{V_b} \right)^3 + \dots$$

Substituting in (8),

(10)

$$50 \quad Y_m = j \left(\frac{-1}{\omega L_3} + \omega C_{10} + \omega C_b \right) \left(\frac{1}{2} \left(\frac{V_m}{V_b} \right) + \frac{3}{8} \left(\frac{V_m}{V_b} \right)^2 + \frac{5}{16} \left(\frac{V_m}{V_b} \right)^3 + \dots \right)$$

55 The problem of providing a voltage-controlled crystal oscillator whose frequency is a linear function of the applied modulating voltage can be better understood by reference to FIGS. 7 and 8 and the following discussion.

60 FIG. 7 is a graph of admittance versus frequency for a conventional construction of a crystal circuit 3 and a modulating circuit 4. The maximum values, or poles, of the admittance Y_x correspond to the series resonance states of the crystal circuit 3, and zero values correspond to parallel resonance states. The dotted line is a plot of $-Y_x$. Superimposed on this graph are values of Y_m , corresponding to three different values of V_m each equally spaced. Assuming that the frequency determining network comprising the circuits 3 and 4 resonates at f_0 with $V_m = 0$, a first increment of modulating voltage ΔV_m will

70 produce an admittance Y_{m1} of the modulating circuit which may have an intersection with the corresponding curve of $-Y_x$ at a frequency f_1 at which the frequency determining network is at resonance. For twice the modulating voltage increment, or $2\Delta V_m$, the admittance Y_{m2} is equal and opposite in value to the admittance Y_x at a

second frequency f_2 . It will be observed that the difference in frequency between f_1 and f_2 is not the same as the difference between f_0 and f_1 . Similarly, a third equal increment of modulating voltage produces a third modulating impedance Y_{m3} that is equal and opposite to the crystal circuit admittance Y_x at a frequency f_3 . It will be obvious that the resonant frequency of the combined circuit as so described is not a linear function of the modulating voltage.

Referring to FIG. 8, in accordance with my invention the components of the crystal circuit of FIG. 5 and the modulating circuit of FIG. 6 are selected so that the admittance curve Y_x has a negative, $-Y_x$, that intersects with the values of Y_m induced by equal increments of the modulating voltage V_m at frequencies f_1 , f_2 , and f_3 that are linearly related to the increments in modulating voltage. The manner in which the components are selected to produce this result will next be described.

First, select the values of L_3 , C_{10} and C_b in the modulating circuit 4 to satisfy the relation:

$$(11) \quad \omega_0^2 = \frac{1}{L_3(C_{10} + C_b)}$$

Thus, in the vicinity of ω_0 ,

$$\left(\frac{-1}{\omega L_3} + \omega C_{10} + \omega C_b \right) \approx 0$$

Then Equation 10 becomes, approximately,

(12)

$$Y_m = j\omega C_b \left[\frac{1}{2} \left(\frac{V_m}{V_b} \right) + \frac{3}{8} \left(\frac{V_m}{V_b} \right)^2 + \frac{5}{16} \left(\frac{V_m}{V_b} \right)^3 \right]$$

Applying the condition

$$Y_m = -Y_x$$

Equations 7 and 12 may be equated, term by term, to give

$$(13) \quad -ryC_0 = \frac{C_b}{2} \frac{V_m}{V_b}$$

$$(14) \quad C_0 r^2 D y^2 = \frac{3}{8} C_b \left(\frac{V_m}{V_b} \right)^2$$

$$(15) \quad -C_0 r^2 (1 + r D^2) y^3 = \frac{5}{16} C_b \left(\frac{V_m}{V_b} \right)^3$$

From (13)

$$(16) \quad y = -\frac{C_b}{2rC_0} \frac{V_m}{V_b}$$

$$(17) \quad \Delta f = -\frac{f_0 C_b}{4rC_0} \frac{V_m}{V_b}$$

Substituting (16) into (14) and rearranging yields

$$\frac{DC_b}{C_0} = \frac{3}{2}$$

$$(18) \quad D = \frac{3C_0}{2C_b}$$

$$(19) \quad \text{Thus, } \Delta f_s = \frac{3}{4} f_0 \frac{C_0}{C_b}$$

Substituting (16) into (15)

$$-(1 + r D^2) \left(-\frac{C_b}{2rC_0} \right)^2 = \frac{5}{2}$$

$$(20) \quad \left(\frac{1 + r D^2}{r} \right) \left(\frac{C_b}{C_0} \right)^2 = \frac{5}{2}$$

From (18)

$$\frac{1}{r} \left(1 + r \frac{9}{4} \frac{C_b^2}{C_0^2} \right) \left(\frac{C_b}{C_0} \right)^2 = \frac{5}{2}$$

$$\frac{1}{r} \left(\frac{C_b}{C_0} \right)^2 + \frac{9}{4} = \frac{5}{2}$$

$$\left(\frac{C_b}{C_0} \right)^2 r = \frac{5}{4}$$

(21)

$$5 \quad \frac{C_b}{C_0} = \frac{\sqrt{r}}{2}$$

From Equations 17, 19 and 21, the basic design criteria are available. The following specifications are typical of an oscillator with a peak deviation of $\pm 0.1\%$.

10	Center frequency	kc./sec.	30,000
Peak deviation	do	30	
Power supply	volts	28	
Linearity of modulation, cps. from best straight			± 300
15 Modulation voltage	v. peak	5	

Size, power, temperature range, modulation input impedance and other parameters can be specified but are not critical to this example.

From considerable experience, it should be observed that a crystal with the largest spot size (i.e., largest C_3) should be employed that is compatible with inharmonic modes. For this example, a crystal with a C_3 of .004 pf. and a static capacitance (C_4) of 1.5 pf. is used. If the total capacitance C_1 (including the stray wiring capacitance) is 0.5 pf., then the ratio $r = 500$.

From Equation 21 the value of C_b is

$$C_b \approx \frac{C_0 \sqrt{r}}{2} \frac{2.0}{2} \sqrt{500} 22.4 \text{ pf.}$$

30 Also from (19)

$$\Delta f_s = \frac{3}{4} f_0 \frac{C_0}{C_b}$$

$$= \frac{3}{4} (30,000) \frac{2}{22.4}$$

$$= 2000 \text{ kc./sec.}$$

From (17)

$$40 \quad -\frac{V_m}{V_b} = \frac{4rC_0}{C_b} \frac{\Delta f}{f_0}$$

$$= \pm 4 (500) \frac{2}{22.4} \times \frac{1}{1000}$$

$$45 = \pm \frac{4}{22.4} = \pm .18$$

$$-V_m \approx \pm .18 V_b$$

From the power supply limit of 28 volts the variable capacitance diode and bias are chosen. For example, a Zener regulated voltage of 18 volts can be conveniently obtained with a 25 volt supply. Thus, the diodes are chosen to obtain approximately 22.4 pf. at a quiescent bias of 18 volts. The voltage required to achieve the modulation is approximately 3.2 volts peak. Thus, a resistor divider can be employed to reduce the specified 5 volts peak to a value of 3.2. Other solutions can be obtained by increasing the value of C_1 , and/or V_b to the limit of increasing V_m to a value of 5 volts peak.

60 FIG. 9 shows a specific embodiment of the apparatus of my invention. As shown, the frequency determining network comprising the crystal circuit of FIG. 3 and the modulating circuit of FIG. 6, connected in parallel, is coupled to the input and output circuits of the amplifier 65 1 by means of a transformer comprising a primary winding L_3 , a secondary winding L_5 connected to the input terminals of the amplifier 1, and another secondary winding L_4 . The winding L_4 is connected in series with inductor L_6 and a capacitor C_{11} to the output terminal 70 of the amplifier 1. The inductance L_3 of this circuit, for use in Equation 11, for example, is the inductance seen across the terminals of the winding L_3 as reflected by the various circuits coupled to the winding.

While the apparatus thus far described is useful for many purposes, it is inherently limited in per cent modula-

tion by adjacent inharmonic modes. FIG. 10 illustrates a typical impedance curve in the vicinity of 30 megacycles per second for a frequency determining network of the type shown in FIG. 2. As shown, the pole typically occurs at, say, 30 kilocycles per second above the zero. An inharmonic mode may occur as close as 60 kilocycles per second above the zero at series resonance. Thus, there is only a clear band 30 kilocycles per second wide on either side of the impedance pole (or admittance zero) at parallel resonance. Therefore, a voltage controlled oscillator in which the crystal is operated at parallel resonance cannot be modulated over a band more than 30 kilocycles per second, on either side of the center frequency, or at a rate of more than 30 kilocycles per second over any band, without distortion introduced by inharmonic resonance. However, a band of 60 kilocycles per second is available above the zero at series resonance.

FIG. 11 shows a theoretical frequency determining network which can be operated in the vicinity of the series resonance of the frequency control crystal while retaining the practical advantages of operation of the modulation circuit at parallel resonance. In FIG. 11, the modulating circuit 4 may be the same as in FIGS. 2 and 6, and has an admittance Y_m . The crystal circuit 3a is adapted for use near the series resonant frequency of the crystal, in a manner to appear, and has an admittance Y_x . Interconnecting the circuits 3a and 4 is a hypothetical "gyrator" network, comprising a negative capacitance $-C_g$ connected across the output terminals a' and b' of the circuit 3a, a negative capacitance $-C_g$ connected across the input terminals a and b of the circuit 4, and a positive (or real) capacitance C_g connected between terminals a' and a . The admittance Y_c of the combined gyrator and crystal circuit 3a, seen by the circuit 4 at the terminals a and b , can be shown by elementary considerations to be:

$$(23) \quad Y_c = -\frac{Y_g^2}{Y_x}$$

If both of the circuits 3a and 4 are tuned so that $Y_m = Y_c$ at ω_0 , where ω_0 is the series resonant frequency of the crystal in the circuit 3a, the effect will be a crystal controlled circuit operated at series resonance but having the impedance characteristics of operation at parallel resonance. And, while Equation 23 is dependent upon the hypothetical gyrator concept, it will be shown below that the same result can be obtained in a real circuit by proper selection of the component values.

FIG. 12 shows an actual crystal circuit suitable for use as the circuit 3a in FIG. 11, and FIG. 13 shows the equivalent circuit in which the symbol for the crystal X has been replaced by a capacitor C_4 connected in parallel with the series combination of an inductor L_2 and a capacitor C_3 . For operation at the series resonant frequency of the crystal, an inductor L_4 and a variable capacitor C_{11} are connected in parallel with the crystal X.

In terms of the equivalent circuit of FIG. 13, the admittance Y_x of the crystal circuit, as seen at the output terminals a' and b' , can be shown to be:

$$(24) \quad Y_x = j\omega(C_4 + C_{11}) + \frac{1}{j\omega L_4} + \frac{1}{j\omega L_2 + \frac{1}{j\omega C_3}}$$

let $C_4 + C_{11} = C_p$

$$(25) \quad Y_x = j\omega C_p \left[1 - \frac{1}{\omega^2 L_4 C_p} + \frac{C_3}{C_p} \left(\frac{1}{1 - \omega^2 L_2 C_3} \right) \right]$$

but by definition $\frac{C_3}{C_p} = \frac{1}{r}$

$$(26) \quad Y_x = j\omega C_p \left[1 - \frac{\omega_s^2}{\omega^2} + \left(\frac{1}{r} \right) \left(\frac{1}{1 - \frac{\omega^2}{\omega_0^2}} \right) \right]$$

$$(27) \quad Y_x \approx j\omega C_p \left[1 - \frac{1 + \frac{2\Delta f_s}{f_0}}{1 + \frac{2\Delta f}{f_0}} + \left(\frac{1}{r} \right) \left(\frac{1}{-2\frac{\Delta f}{f_0}} \right) \right]$$

approximating the denominator

$$Y_x = j\omega C_p \left[1 - \left(1 + \frac{2\Delta f_s}{f_0} \right) \left(1 - \frac{2\Delta f}{f_0} \right) - \frac{1}{2r \frac{\Delta f}{f_0}} \right]$$

$$\text{Let } y = \frac{2\Delta f}{f_0} \text{ and } D = \frac{2\Delta f_s}{f_0}$$

$$(28) \quad Y_x \approx j\omega C_p \left[y - D + yD - \frac{1}{ry} \right]$$

$$(29) \quad Y_x = -\frac{j\omega C_p}{ry} [1 + rDy - ry^2 + D]$$

From (23)

$$Y_c = -\frac{Y_g^2}{Y_x} = \frac{\omega^2 C_g^2}{Y_x}$$

$$(30) \quad Y_c = \frac{\omega^2 C_g^2 ry}{-j\omega C_p} \left[\frac{1}{1 + rDy - ry^2(1 + D)} \right]$$

$$Y_c = +j\omega \frac{C_g^2 r}{C_p} y [1 - rDy + ry^2(1 + D) + r^2 D^2 y^2]$$

$$(31) \quad Y_c = +j\omega \frac{C_g^2 r}{C_p} y [1 - rDy + ry^2(1 + D + rD^2)]$$

Letting $Y_c = -Y_m$, and for that purpose equating Equations 10 and 31 term by term while accounting for the negative sign, the following conditions are obtained.

$$(32) \quad \frac{C_g^2 ry}{C_p} = -\frac{C_b V_m}{2V_b}$$

$$(33) \quad \frac{C_g^2 ry}{C_p} - (rDy) = -C_b \frac{3}{8} \left(\frac{V_m}{V_b} \right)^2$$

$$(34) \quad \frac{C_g^2 ry}{C_p} (ry^2)(1 + D + rD^2) = -C_b \frac{5}{16} \left(\frac{V_m}{V_b} \right)^3$$

From Equation 32

$$(35) \quad y = -\frac{C_b C_p V_m}{2C_g^2 r V_b} = -\frac{C_b C_{1x}}{2C_g^2} \left(\frac{V_m}{V_b} \right)$$

substituting (35) into (33) and (34)

$$(36) \quad \frac{C_b C_p D}{C_g^2} = \frac{3}{2}$$

$$(37) \quad D^2 - \frac{9}{r} D - \frac{9}{r} = 0$$

Equation 37 may be solved without approximation. However, with an error less than 10% for most applications Equation 37 may be approximated by:

$$(38) \quad D = \frac{3}{\sqrt{r}}$$

From (36)

$$(39) \quad \frac{C_b C_p}{C_g^2} = \frac{\sqrt{r}}{2}$$

Thus, the value of modulation capacitance C_b is

$$(40) \quad C_b = \frac{\sqrt{r}}{2} \frac{C_g^2}{C_p} = \frac{C_g^2}{2\sqrt{r} C_3}$$

From (38)

$$(41) \quad f_s = \frac{1.5 f_0}{\sqrt{r}}$$

From the above equations, and conventional design considerations, the values of the passive components can be selected. The actual selection of values is similar to

the previous example. It is of value to recite that an additional degree of freedom is obtained in the selection of the component value of the gyrator capacitance.

FIG. 14 shows the complete circuit of FIG. 11, including the circuits of FIGS. 6 and 12 and the gyrator connected in parallel. In order to construct an actual circuit performing in accordance with the theoretical performance of the circuit of FIG. 14, the negative capacitances in the gyrator are absorbed by lumping with real constants. FIG. 15 shows a practical circuit useable where the calculated value of C_g is less than either C_{10} or C_{11} . Capacitors C_{10} and C_{11} , having capacitances $C_{10}-C_g$ and $C_{11}-C_g$, respectively, are used. Should the value of C_g be larger than C_{10} or C_{11} , substantially the same result could be obtained by substituting an inductance. For example, if $C_{10}-C_g$ is negative, an inductor having an inductance

$$L = \frac{1}{\omega_0^2(C_g - C_{10})}$$

would be substituted for the capacitor C_{10} .

FIG. 16 shows a preferred embodiment of the linear variable frequency crystal controlled oscillator of my invention. The apparatus includes the crystal circuit of FIG. 12, comprising a tuning capacitor C_{12} and a coupling capacitor C_{13} corresponding to C_g in FIGS. 11, 14 and 15. C_{12} has a capacitance $C_{11}-C_{13}$ connected in parallel with the inductor L_4 and the crystal X. The modulation circuit is similar to the circuit of FIG. 6, except that two variable capacitance diodes D_1 and D_2 in parallel have been used. Two diodes are used to obtain a larger value of capacitance C_b that can conveniently be obtained with one. The bias voltage V_b is applied through two resistors R_2 and R_3 in series, and a smoothing capacitor C_{19} is connected between the junction of the resistors R_2 and R_3 and ground. The modulating voltage V_m is applied through a resistor R_1 , connected in series with a potentiometer P_1 comprising a modulation sensitivity control. The output voltage of the frequency determining network is applied to the input of the amplifier by means of a voltage divider comprising a pair of capacitors C_{16} and C_{17} connected in series. The capacitor C_{14} has a combined capacitance equal to $C_{10}-C_{13}$. Feedback to the amplifier is provided through a variable capacitor C_{20} in series with an inductor L_6 from the junction of the capacitors C_{16} and C_{17} .

While I have described my invention with respect to the details of various illustrative embodiments thereof, many changes and variations will occur to those skilled in the art upon reading my description, and such can obviously be made without departing from the scope of my invention.

Having thus described my invention, what I claim is:

1. A variable frequency crystal-controlled oscillator of the class comprising an amplifier having a regenerative feedback network for determining operating frequency, in which said feedback network includes a modulating circuit connected in parallel with a crystal circuit, said modulating circuit having a voltage controlled reactive impedance that is a non-linear function of applied modulating voltage and a group of passive reactive impedances connected in said circuit, said passive reactive impedances having reactances selected to make the admittance Y_m of the modulating circuit substantially directly proportional to frequency over the range of modulation, whereby $Y_m = G_1(V_m, f)$, where f is frequency, V_m is the modulating voltage, and G_1 is said non-linear function, said crystal circuit comprising a frequency controlling crystal and passive reactive impedances connected in said

crystal circuit having reactances selected so that the admittance Y_x of the crystal circuit may be expressed as $Y_x = G_2(f)$ over the range of modulation where G_2 is a non-linear function of f , and the sum

$$\sum_{i=1}^{\infty} (a_i - b_i)$$

equals approximately zero, where a_i represents a term in a convergent infinite series expansion of $G_1(V_m)$ and b_i represents the corresponding term in a similar convergent infinite series expansion of $G_2(f)$.

2. A frequency determining network for a variable frequency crystal controlled oscillator, comprising a voltage responsive impedance having a reactance non-linearly related to applied modulating voltage connected in a modulating circuit with a first group of reactive impedances, the reactances of said first group being selected to make the admittance of the modulating circuit proportional to frequency over a desired range of frequencies, a crystal circuit comprising a frequency control crystal and a second group of reactive impedances, the reactances of said second group being selected to shape the response to frequency of the admittance of the crystal circuit to compensate for the non-linear response to voltage of the voltage responsive impedance, and means connecting the crystal circuit in parallel with the modulating circuit.

3. The apparatus of claim 2, in which said connecting means comprises a capacitor; said capacitor having a capacitance selected, and one reactance of each group being further selected, such that the impedance of the crystal circuit is reflected as an admittance to the modulating circuit, and in which said reactances are further selected so that the frequency determining network is at parallel resonance when the crystal is at series resonance.

4. The apparatus of claim 2, in which said connecting means is substantially non-reactive, and in which said impedances are selected so that the frequency determining network is at parallel resonance when the crystal is at parallel resonance.

5. A frequency determining network, comprising a crystal circuit comprising a first inductor and a first capacitor connected in parallel; a modulating circuit comprising a voltage responsive capacitor having a non-linear characteristic; a second inductor, and a third capacitor connected in parallel; and means connecting said first circuit and said second circuit in parallel; said third capacitor, said second inductor and said voltage responsive capacitor having values selected to be in resonance at a resonant frequency of said crystal, and said first capacitor and said first inductor having values chosen to shape the response to frequency of the admittance of said crystal circuit to cause the parallel resonant frequency of said frequency determining network to vary linearly with modulating voltage applied to said modulating circuit.

6. The apparatus of claim 5, in which said resonant frequency of said crystal is the series resonant frequency of the crystal, in which said connecting means comprises a fourth capacitor, and in which said fourth capacitor is selected, and said first and third capacitor are further selected, to reflect the impedance of the crystal circuit as an admittance to the modulating circuit.

7. The apparatus of claim 5, in which said resonant frequency of said crystal is the parallel resonant frequency of the crystal, and in which said connecting means is resistive.
